UNITED STATES PATENT OFFICE.

THOMAS E. MURRAY, OF NEW YORK, N. Y.

SHEET-METAL PISTON.

1,215,969.

Specification of Letters Patent. Patented Feb. 13, 1917.

Application filed December 14, 1916. Serial No. 136,861.

To all whom it may concern:

Be it known that I, THOMAS E. MURRAY, a citizen of the United States, residing at New York, in the county of New York and 5 State of New York, have invented a certain new and useful Improvement in Sheet-Metal Pistons, of which the following is a specification.

The invention is a piston having internal

10 sleeves for the reception of the piston rod pin, the said piston and sleeves being formed of struck up sheet metal, with the parts united by electrically welded joints, and a method of making said piston.

15 In the accompanying drawings—

Figure 1 represents the blank from which one of the half sections of the piston is made. Fig. 2 is an elevation, and Fig. 3 is a transverse section of one of said half sections.

20 Fig. 4 is a section similar to Fig. 3, with one of the internal sleeves electrically welded in place. Fig. 5 is a section on the line $x-x$ of Fig. 6, of the completed piston. Fig. 6 is a section on the line $y-y$ of Fig. 5, showing the cover plate electrically welded in place.

Similar letters of reference indicate like parts.

The blank A, Fig. 1, from which each half 30 section of the piston is formed, is a parallelogram of sheet metal of suitable dimensions. In said blank I produce by striking up or stamping, a circular opening B and a flange or rib C surrounding said opening. I then 35 bend the blank into semi-circular form, and at the same time strike up the channels D for the reception of the usual packing rings or gaskets. I then electrically weld to the rib C, the butt end of a sleeve E, also of 40 sheet metal. I produce in this way, two similar half sections A, A', Fig. 5. I then electrically weld the longitudinal edges of said half sections, as shown at F. To one end of the cylinder thus produced, I weld 45 electrically the head G, which I also stamp from sheet metal, preferably with an integral circular struck up strengthening rib H.

The sleeves E are designed to receive the usual pin by which the piston rod is connected to the piston, said rod then entering 50 the piston through the open end thereof, and

into the space between the inner ends of said sleeves E.

In this way, I produce a piston wholly of sheet metal, with its parts connected by electrically welded joints, thus forming a complete homogeneous and strong structure. No machining is required to fit the parts, and the cost of manufacture is largely reduced.

I claim:

1. A piston, comprising a hollow cylinder having diametrically opposite circular openings in its wall, and integral in-turned flanges surrounding said openings, a cylinder head, and sleeves respectively united at 65 their outer ends to said flanges and separated at their inner ends: the said cylinder sleeves and head being formed of struck up sheet metal and united by electrically welded joints.

2. A piston, comprising a hollow cylinder having diametrically opposite circular openings in its wall, and integral in-turned flanges surrounding said openings and circumferential grooves on the exterior of said 70 wall, a cylinder head, and sleeves respectively united at their outer ends to said flanges and separated at their inner ends: the said cylinder, sleeves and head being formed of struck up sheet metal and united 75 by electrically welded joints.

3. A cylindrical piston of sheet metal, comprising two semi-cylindrical half sections, each formed by striking up the sheet, the said sections being united at their longitudinal edges, an internal circular rib integrally formed on the concave side of each section, the said ribs surrounding diametrically opposite circular openings in said sections, a cylinder head, and sleeves united at 85 their outer ends to said ribs, the said sleeves being in line and having their inner ends separated: the said sections, sleeves and head being formed of struck up sheet metal and united by electrically welded joints.

4. The method of making a hollow cylindrical piston of sheet metal, which consists in, first, forming on each of two flat sheets a circular opening and an integral flange surrounding said opening, second, bending 100 each of said sheets to form a semi-cylindrical half section, with said flange on its con-

cave side, third, electrically butt-welding to said flanges, sleeves, each of a length less than the semi-diameter of said piston, fourth, electrically welding together said 5 semi-cylindrical sections at their longitudinal edges, and fifth, electrically welding a head of sheet metal to one end of said piston.

In testimony whereof I have affixed my signature in presence of two witnesses.

THOMAS E. MURRAY.

Witnesses:
